Primary Examiner — Cathron C Brooks*Assistant Examiner* — Sharon S Oum(74) *Attorney, Agent, or Firm* — Faegre Baker Daniels LLP**CLAIM**

The ornamental design for a vent, as shown and described.

DESCRIPTION

FIG. 1 is a front perspective view of a vent illustrating my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines illustrate portions of the vent that form no part of the claimed design.
